Atty.

UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

GRINDING MACHINE.

1,412,026.

Specification of Letters Patent. Patented Apr. 4, 1922.

Application filed October 22, 1921. Serial No. 509,495.

To all whom it may concern:

Be it known that I, THOMAS J. STURTEVANT, a citizen of the United States, residing at Wellesley, in the county of Norfolk and State of Massachusetts, have invented an Improvement in Grinding Machines, of which the following description, in connection with the accompanying drawings, is a specification, like characters on the drawings

10 representing like parts.

The invention to be hereinafter described relates to machines for grinding or reducing materials such, for example, as phosphate rock, coal, ores, cement and cotton seed.

15 It is desirable to grind samples of the materials from time to time for purposes of laboratory analysis. These samples are of predetermined amount and each sample should be completely reduced and entirely 20 removed from the machine. This makes it necessary to brush the dust from the inner surfaces of the casing of the machine and the mechanism contained therein.

One of the purposes of the present invention, therefore, is to provide a machine which is so constructed that convenient, easy access may be had to the inner surfaces of the casing and the mechanism contained therein. As a consequence, the dust may be readily 30 brushed therefrom and collected as a part of the sample reduced. Also, if the machine is used to grind different materials, the parts may be readily cleaned to prevent mixing of dust from one sample with dust of another 35 sample of different material.

Sometimes materials between the grinding members may produce grooves in the surfaces thereof or otherwise disfigure the same.

40 Another purpose of the invention, therefore, is to provide means to enable relative adjustment or displacement of the grinding members so that on further operation of the grinding members, such grooves or other disfigurement may be removed.

Sometimes abnormally large or hard materials may come between the surfaces of the grinding members with liability of consequent injury thereto.

45 Another purpose of the invention, therefore, is to provide yielding means to enable one of the grinding members to move away from the other grinding member, and thereby prevent such injury to the members.

50 Still another purpose of the invention is

to provide a simple, efficient machine for the purposes, which may be easily manufactured with economy of material.

With the aforesaid and other purposes in view, the character of the invention may be best understood by reference to the following description of one good form thereof shown in the accompanying drawings, wherein:

Fig. 1 is a plan of the machine;

Fig. 2 is a vertical longitudinal section taken on line 2—2 of Fig. 1;

Fig. 3 on an enlarged scale is a vertical transverse section taken on line 3—3 of Fig. 1;

Fig. 4 is an end elevation of the machine;

Fig. 5 is a side elevation of a portion of the machine showing the chamber of the casing in open position; and

Fig. 6 on an enlarged scale is a vertical transverse section taken on line 6—6 of Fig. 1.

The machine shown herein as one good form of the invention, comprises a suitable support, in the present instance, in the form of a base 1 (Figs. 1 and 2) having holes 3 adapted to receive bolts for securing the same in position. Rising from the base are uprights 5 and 7 which may have bores 9 adapted to receive bearings of suitable construction.

In the present instance of the invention, roller bearings are provided, each comprising a series of rollers 11 formed of helically wound ribbon material of resilient character. At opposed ends of the rollers are washers 13 connected at intervals by rods 15 located in spaces between the rollers. The washers may be confined by inner rings 17 and outer rings 19 which may be tightly fitted or otherwise secured in the bores 9. These bearings may be lubricated by suitable grease cups 21.

A horizontal shaft 23 is journaled in these roller bearings, and in the present instance, is provided with a fast pulley 25 and a smaller loose pulley 27 mounted on the shaft intermediate the bearing supports.

The shaft 23 has an end portion 29 projecting a substantial distance beyond the right hand bearing (Fig. 2), and serves to support a grinding member 31, in the present instance, comprising a disk 33 having a hub 35 secured by a key 37 on a reduced end of the shaft portion 29. A ring 39 has

a central aperture 41 adapted to fit on the hub 35, and said ring is detachably secured to the disk 33 by screw bolts 43. This ring may have a suitable grinding surface, in 5 the present instance, comprising radial ribs 45 tapering toward a smooth surface intermediate the ends of the ribs and the periphery of the ring. This grinding member is adapted to co-operate with an opposed fixed 10 grinding member 47 provided with radial ribs 49 tapering toward a smooth portion between the ends of the ribs and the periphery of the member.

The grinding members may be enclosed 15 in a casing 51 which is constructed to enable ready access to the grinding members and the inner surfaces of the casing, in order that after material has been ground, any residual dust on said parts may be brushed 20 therefrom.

The casing, in the present instance, comprises a fixed plate or member 53 which may be suitably supported. To accomplish this, in the present instance, said plate is provided with an extension 55 bored to receive 25 the shaft and terminating in a boss formed to fit in the bore 9 for the right hand bearing. This boss may also constitute the right hand ring 19 referred to, for one of the 30 roller bearings.

To secure the casing plate 53 to the upright 7, a pair of through bolts 57 (Fig. 1) may be entered through the plate and through the base upright 7. Preferably these 35 through bolts are in the same plane with the axis of the shaft 23 and the boss or ring 19, thereby rigidly to secure the plate to the support and effectively resist rocking strains of the casing plate on its support. 40 Suitable means may be provided to prevent dust from working along the shaft 23 from the casing to the right hand bearing. This means, in the present instance, is in the form of a chamber 59 (Fig. 2) formed 45 in the plate extension 55 about the shaft, and provided with an outlet 61. The construction is such that any dust working from the casing along the shaft through the bore in the casing plate, will enter the chamber 59 and be delivered therefrom through 50 the outlet 61. As a consequence, the dust cannot enter the right hand bearing and cause injury thereto.

The casing 51 may have a body 63 provided with a chamber 65 of sufficient width to accommodate the grinding members. This chamber has an open side 67 which is normally closed by the casing plate 53.

The body 63 may be connected to the 60 plate 53 by suitable hinge means, in the present instance, comprising a pair of lugs 69 projecting from the plate 53, and a pair of lugs 71 projecting from the body 63. These lugs have registering bores receiving 65 a shaft 73 which may be secured to one of

the lugs of the fixed plate 53 by a set screw 75 or other suitable securing means. The lower end of the shaft 73 may have a threaded portion 77 receiving an adjusting nut 79 and a lock nut 81, the former being 70 adapted to engage the under side of the lower lug of the casing body 63. The construction is such that the body 63 may be adjusted relatively to the fixed plate 53 and the grinding member carried by the shaft, 75 for a purpose to be described.

To hold the body in closed position, it may have suitable securing means, in the present instance, comprising a latch having a yoke 82 (Fig. 1) fulcrumed on a pin 80 82^a carried by a lug 82^b projecting from the casing body. This yoke is adapted to swing over a lug 83 projecting from the fixed plate, and be secured by a set screw 85.

The grinding member 47 referred to, may 85 be detachably secured to the body of the casing by suitable means, in the present instance, in the form of screw bolts 87 (Figs. 1 and 2) desirably located in a horizontal plane cutting the axis of the shaft 23.

The grinding member 47 carried by the body may have a central aperture 89 registering with the throat 91 of a hopper 93 which may be formed on and carried by the casing body. The construction is such that 95 materials introduced into the hopper 93 will pass through the throat 91 and the aperture 89 to the space between the opposed faces of the grinding members for reduction thereby.

As stated, one of the purposes of the present machine is to grind or reduce samples of various materials for the purpose of laboratory analysis. Suitable means may be provided to receive a sample after it has been 105 reduced. This means, in the present instance of the invention, comprises a drawer 95 adapted to slide in guides 97 at the bottom of the casing body, said drawer being provided with a suitable handle 98. The construction is such that the materials reduced on relative rotation of the grinding members, will be guided by the inner walls of the casing down into the drawer.

As stated, it is necessary that the complete sample reduced shall be retained. This makes it necessary to have ready access to the inner surfaces of the casing and the parts contained therein, in order that any residual dust thereon may be brushed therefrom. 120 The construction described lends itself advantageously to this purpose. After a sample has been ground, the latch set screw 85 may be released to permit the yoke 82 to be swung away from the plate lug 83. 125 Thereupon, the casing body which carries the grinding member 47 and the hopper 93 and the drawer, may be swung on the hinge means away from the casing plate 53. As a consequence, the grinding member 47 car- 130

ried by the casing, is swung away from the grinding member 31 carried by the shaft, as will be noted in Fig. 5, thereby exposing the inner surfaces of the casing, the surfaces of 5 the grinding members, and other parts contained within the casing, so that dust thereon may be readily brushed therefrom into the drawer. It will be noted that the grinding member 33 is mounted on its shaft a substantial distance away from the casing plate 53, thereby affording room between them to enable dust on their surfaces to be brushed therefrom. After the dust has been removed, the casing body may be swung on its 10 hinge to closed position, and the latch may be secured.

It is desirable to be able to adjust one of the grinding members relatively to the other to vary the space between them. To accomplish this, in the present instance, the left 20 end of the shaft 23 may be extended beyond the left bearing into a head 99 (Figs. 1 and 2). Threaded into this head is an adjusting screw 101 provided with a hand wheel 103. A hand wheel lock nut 105 on the adjusting 25 screw is adapted to bear against the end of the head to secure the former in its different positions of adjustment. Interposed between the inner end of the adjusting screw 30 and the end of the shaft is a thrust button 107 having lugs 109 (Fig. 3) projecting therefrom into guideways 111 formed in the head. The engaging faces of the end of the shaft and the thrust button may be lubricated by means of a grease cup 113.

The construction is such that when materials are introduced between the grinding members, pressure will occur tending to thrust the shaft 23 axially toward the left 40 (Fig. 2), thereby causing its end to bear against the thrust button. Since the thrust button is confined against rotation, it will prevent any tendency to rotate the adjusting screw 101 such as might destroy its proper 45 adjustment. On release of the hand wheel nut 105, the adjusting screw may be turned to adjust the shaft axially to vary the space between the grinding members according to conditions as required.

50 It is desirable to provide means to allow yielding movement of the shaft in an axial direction when abnormal materials come between the grinding members, in order to prevent injury thereto. To accomplish this, in the present instance, the head 99 referred to, may be provided with a pair of coil springs 55 115 (Figs. 1 and 3) mounted in sockets 117 formed in the head. These springs may be confined between the bottoms of the sockets 60 and washers 119 mounted in the sockets and limited by adjusting nuts 121 held by lock nuts 123, said nuts being threaded to through bolts 125 entered through the sockets and through the base upright 5 referred to.

These coil springs will react against the washers and nuts so as normally to hold the head against the outer face of the upright, but if abnormal materials come between the grinding members, the shaft will be thrust somewhat toward the left (Fig. 2) and through the thrust button, adjusting screw and head will compress the coil springs and move the head away from the face of the upright. As a result, injury to the faces of 75 the grinding members from such cause is prevented.

In the course of use the surfaces of the opposed grinding members may become grooved or scored circumferentially thereof. 80 To remove such disfigurement from the surfaces, the adjusting nut 79 on the hinge shaft may be adjusted to raise or lower the body of the casing, thereby to move the grinding member 47 carried by the body 85 of the casing to a position somewhat eccentric to the grinding member carried by the shaft. As a consequence, on further rotation of the grinding member carried by the shaft, such disfigurement to the surfaces 90 may be ground off and removed.

When the machine is employed as a sample grinder, the sample is introduced into the hopper 93 and passes thence downward and laterally through the throat 91 and 95 aperture 89 to the space between the grinding members, and the reduced sample is collected in the drawer 95. Then the body of the casing may be swung to open position to enable the residual dust to be brushed from 100 the inner surfaces of the casing and the grinding mechanism therein into the drawer. Thus, the complete sample is collected and ready for laboratory analysis or other purpose as required. 105

Since the grinding member carried by the shaft is a substantial distance from the fixed plate of the casing, the rear face of the grinding member and the inner surface of the fixed plate are accessible to enable dust 110 to be brushed therefrom. If desired, greater accessibility to the surfaces may be had by grasping the grinding member carried by the shaft and pulling the same forward until limited by engagement of the hub of the 115 fixed pulley with the base upright 7.

In some cases it may be desirable to use the machine as a continuous grinder. To accomplish this, the drawer 95 may be removed, and the reduced materials may be 120 delivered into a suitable chute leading to an appropriate collecting receptacle.

It will be noted that the body of the casing is hinged to the fixed plate on a vertical axis. This enables the body and the hopper, grinding member and drawer carried by the body, to be easily and readily swung to open position, and without the necessity for lifting the body, as would be necessary if it were hinged on a horizontal axis. 125 130

The construction is such that the parts contained within the casing may be quickly and readily accessible for purposes of inspection, replacement or repair thereof.

- 5 From time to time it will be necessary to substitute new grinding rings for worn ones, and to substitute rings having grinding surfaces of different character according to the class of materials to be reduced. The 10 ready accessibility to the supports for these grinding rings, enables such substitution to be made in minimum time.

The roller bearings described are a desirable feature, not only because they materially reduce the friction on the shaft, but also because they enable the shaft to readily slide in the direction of its axis against the resistance of the spring-pressed head during the operation of the machine, 15 without liability of scoring or grooving the shaft, and consequent interference with its free axial movement.

The machine described is simple in construction, cheap to manufacture, and not 20 liable to get out of order.

It will be understood that the invention is not limited to the specific embodiment shown, and that various deviations may be made therefrom without departing from the 25 spirit and scope of the appended claims.

What is claimed is:

1. A machine of the character described, comprising, in combination, a support provided with bearings, a casing having a wall 30 plate mounted on said support and a chamber hinged to said wall plate, a shaft journalled in said bearings and projecting through said plate, and grinding members, one on said shaft and the other on said 35 chamber, the latter having a depth sufficient completely to receive both of said members when the hinged chamber is closed and separating and exposing said members when the hinged chamber is opened, thereby furnishing access to said members and the inner 40 surfaces of said plate and chamber to enable ready removal of dust therefrom.

2. A machine of the character described, comprising, in combination, a support provided with cylindrical roller bearings, a shaft journalled in said roller bearings and having an end portion projecting a substantial distance beyond one of said bearings, a casing having a wall fixed to said 50 support adjacent one of said bearings, and a chamber having an open side normally closed by said fixed wall, hinge means connecting said chamber and fixed wall, that the former may swing to open and closed positions, means to secure the chamber in closed position, grinding members mounted in the chamber and on the end portion of said shaft respectively, and means including a spring 55 enabling movement of said shaft parallel to the direction of the axes of the cylindri-

cal roller bearings relatively to the latter to prevent injury to the grinding members on entrance of abnormally large materials between them.

3. A machine of the character described, 70 comprising, in combination, a support provided with bearings, a shaft journalled in said bearings, a casing comprising a fixed wall and a chamber hinged to the fixed wall, the latter having an extension secured to the support and apertured to receive the shaft, and grinding members on the shaft and chamber respectively, said extension being provided with a chamber about the shaft having an outlet to prevent dust, working 75 from the casing along the shaft, from entering one of the shaft bearings.

4. A machine of the character described, comprising, in combination, a support provided with bearings, a shaft journalled in 80 said bearings, a casing comprising a chamber having an open side and a wall normally closing said open side, hinge means connecting said side and chamber, opposed grinding members, one mounted on said shaft and the 85 other mounted on said chamber, said hinge means having provision for adjusting the chamber relatively to said side to enable rotation of the shaft grinding member eccentrically to the chamber grinding member 90 to remove grooves or scorings on the faces 95 of the grinding members.

5. A machine of the character described, comprising, in combination, a support provided with bearings, a shaft journalled in 100 said bearings, a casing comprising a chamber having an open side and a fixed wall normally closing the open side, means to secure the wall to said support, hinge means connecting said chamber and wall, grinding 105 members respectively mounted on the chamber and shaft, a hopper on the chamber for delivering materials into the latter between the grinding members, and a drawer on the chamber for receiving the materials reduced 110 by the grinding members, said chamber, the grinding member thereon, the hopper and the drawer being movable with the chamber away from the fixed wall and shaft grinding member when the chamber is swung on 115 its hinge means into open position.

6. A machine of the character described, comprising in combination, a support, a shaft mounted on said support, a casing comprising a part fixed on said support and 120 a hollow part hinged to said first-named part on a substantially vertical axis, and opposed grinding members, one secured on said shaft a substantial distance from the fixed part of said casing, and the other mounted 125 on said hinged part, the latter enclosing both of said grinding members when closed, both sides of the grinding member on the shaft, the face of the grinding member on the hinged part of the casing, and the inner 130

surface of the casing being exposed to enable removal of dust therefrom when the hinged part of the casing is swung on its hinge to open position.

- 5 7. A machine of the character described, comprising, in combination, a support, a shaft mounted on said support, a casing comprising a part fixed on said support and a part hinged to said fixed part, opposed 10 grinding members, one mounted on the shaft and the other mounted on the hinged part of the casing, and means to adjust the grinding member on said hinged part of the casing to a position eccentric with respect to the 15 axis of said shaft to enable grinding of grooves or other deformations from the faces of the grinding members on relative rotation of the same.
8. A machine of the character described, 20 comprising, in combination, a support having standards provided with aligned bores therein, bearings mounted in said bores, a shaft journalled in said bearings and having an end portion projecting a substantial 25 distance beyond one of them, a casing having a fixed part bored to receive the end portion of said shaft and having a supporting boss mounted in the bore of one of the uprights,

said casing having a chamber hinged to said fixed part, means to secure the chamber in 30 closed position, and opposed grinding members, one carried by said chamber and the other carried by the end portion of said shaft for reducing materials introduced between them. 35

9. A machine of the character described, comprising, in combination, a support having an upright provided with a bore having a bearing, a shaft journalled in said bearing and having an end portion projecting a 40 substantial distance beyond said bearing, a casing comprising a fixed part and a chamber hinged to said fixed part, the latter being formed to present a boss for receiving said shaft and fitted into the bore in the 45 upright, a pair of bolts in substantially the same plane as the axis of said boss for securing the fixed part of the casing to said upright, and grinding members enclosed by said casing, one being carried by said chamber and the other being carried by the end portion of said shaft. 50

In testimony whereof, I have signed my name to this specification.

THOMAS J. STURTEVANT.
